UNITED STATES PATENT OFFICE.

ROBERT HUTCHISON ANDERSON, OF GERMISTON, TRANSVAAL.

ROCK-DRILL.

No. 893,596.

Specification of Letters Patent.

Patented July 21, 1908.

Application filed December 27, 1905. Serial No. 293,485.

To all whom it may concern:

Be it known that I, ROBERT HUTCHISON ANDERSON, a citizen of the United States of America, surveyor, and resident at the May 5 Consolidated Gold Mining Company, Limited, Germiston, District of the Witwatersrand, Colony of the Transvaal, have invented certain new and useful Improvements in Rock-Drills, of which the following is a specification, reference being had therein to the accompanying drawings.

The object of the present invention is to provide a novel form of drill for boring rock percussively, having a separable head attached in a special manner to the shank. The head is such that it may conveniently be cast in steel or otherwise manufactured of hard material at a low price, so that while operating during use more efficiently than 15 the usual present drills, it may economically be thrown away when blunted or destroyed and replaced by a fresh one. Thus the expensive lowering and raising of large quantities of drills into and from a mine and the 20 cost of maintaining a blacksmith's shop for drill forging are both obviated.

According to this invention the separable head is formed with any desired form of cutting edge and at the base is shaped to fit 25 snugly upon the correspondingly formed end of the shank by simple backward pressure.

It has been the practice heretofore to secure the separable head to the shank by using a rigid metal rod, passing through the head, 30 and shank. The disadvantage of this method lies in the fact that the constant shocks and strain to which the rod are subjected tend to crystallize the particles thereof in places, and thus weaken the rod and make 35 it necessary to replace the same at frequent intervals. To obviate this difficulty I pass rearwardly from the head a pliant or flexible 40 tension and securing member, preferably wire or chain, which extends to a tightening 45 and holding device, located upon the shank at a point so far back that it need not enter the bore hole during use of the drill. Upon a yielding member of this character, the 50 shocks and jars incident to percussive boring of rock have no perceptible detrimental effect.

By way of example, the accompanying drawings illustrating an embodiment of the invention are appended. Therein Figure I is a side elevation, partly in section, of an 55 improved drill, Fig. II a view at right angles

to Fig. I with the bit or head removed, Fig. III an end view of Fig. II; Figs. IV and V are enlarged perspective views of the head or bit, as seen from above and below respectively; Fig. VI shows the invention applied to a hand jumper Fig. VII is an end view of Fig. VI. Figs. VIII and X are side elevations of modified forms of drills constructed in accordance with my invention and Fig IX is a section on line 9—9 of Fig. VIII.

1 indicates the drill shank upon the outer end 2 of which the head or bit 3 is located. Their contiguous faces are preferably flat, the better to withstand the transmitted compressive stresses. Bosses 4 project from the 60 periphery of the underside of the head and fit into corresponding recesses 5 in the shank-end, their purpose being to preclude lateral or rotative movement of the head upon the shank. To a lug 6 upon the underside of the 65 head is attached a flexible wire or chain 7, which, in fixing the head, is passed down the axial hole 8 in the shank to a bolt 9 which spans a recess 10 formed in the shank near to the rear end thereof. The wire 7 is attached 70 to the bolt 9, by passing its end through a hole 11 therein or otherwise, and is wound thereon by turning the bolt head with a spanner; a nut 12 upon the bolt locks the same 75 when the wire is sufficiently tight to thoroughly secure the head.

It will thus be manifest that while the head is perfectly firm to resist compressive 80 stresses due to the impacts of the drill and is also incapable of displacement by any ordinary force tending to draw it off the shank, the device by which it is secured is almost entirely without the bore hole and does not interfere with the free working of the drill in 85 the hole, or the passing of the crushed rock 90 therefrom.

As before mentioned the novel construction permits the economical use of heads or bits having more complicated and efficient cutting elements than those of the present 100 solid drills, which are restricted to easily forged patterns. Thus that illustrated by Figs. IV and V is readily cast in steel and has its parts advantageously disposed for breaking the rock inwardly towards the center of 105 the hole. It comprises a leading central point or punch 13, a series of chisel edged wings 14 which enlarge the hole made by the punch and a following series of teeth 15 which operate upon the remaining rock sur- 110

face to further enlarge and clean out the hole to its ultimate size. Again the head shown in Figs. VI and VII includes a central punch 16 cutting or splitting edges 17 followed by 5 reamers 18 curved both radially to smooth out the hole and backwardly at the extremities to avoid undue attrition at those points; the configuration being obviously incapable of production on a commercial basis by forging. Any or all of the cutting edges of either head described may be serrated as indicated at 19 to prevent premature flattening.

The hand jumper shown in Figs. VI and VII embodies the hereinbefore described 15 cutting head with its fixing means and in addition a modification of the invention having for its object the preservation of that end of the jumper which is struck by the hammer. In this instance a separable cap 20 is fitted 20 over such end and secured similarly to the cutting head, *i. e.* by a wire 21 passing down and secured to a bolt 22 arranged in the same recess 10 as the bolt 9.

It will be clear that while adhering to the 25 essential broad features of the invention numerous modifications of the specific constructions described are permissible. Thus instead of the single wire or chain 7 passing down the axial hole 8, a plurality of such 30 wires or chains may be carried down corresponding channels 8' formed externally of the shank as shown in Figs. VIII and IX, the fixing and tightening means being modified or not. Again, in the case of a machine 35 drill the axial hole 8 may be continued to the rear extremity of the shank and the wire replaced by a secured rod 7', which is secured by a nut 20' working upon it and bearing against the shank end as shown in Fig. X.

40 It will be noted that, in each of the embodiments of my invention illustrated the tension means is adapted to permit of a slight angular (tilting) movement of the head relative to the shank upon impact of said head 45 against the rock, particularly where one side only of the head bears the shock or strain of the impact. In the practical use of my drill first one outer chisel or cutting edge and then another is required to bear the entire, or a 50 disproportionately large share of the shock or strain of the impact of the head against the rock. This causes the head to tilt or rock slightly on the shank owing to the enormous pressure exerted on one side of the 55 head, which results in a slight compression of the metal at the lower end of the shank rearward of said side of the head or a wearing or chipping off of the peripheral edge of the lower end of the shank which cannot be avoided even by the use of the hardest and 60 toughest steel available.

In the use of my drill the tension means which I employ permits the cutting head to tilt or rock slightly on the shank upon impact against the rock by virtue, either of its

being flexible throughout its length or by virtue of the way in which the tension means holds the head, as by a non-rigid engagement.

I claim as my invention:

1. In a rock drill, a shank, a separable cutting head adapted to be secured to the lower end thereof, and tension means adapted to secure said head upon said shank, said tension means being adapted to permit of a slight angular movement of said head relative to the said shank upon impact of the cutting head against the rock.

2. In a rock drill, a shank, a separable cutting head adapted to be secured to the lower end thereof, the contiguous faces of 80 said shank end and head being substantially flat, and tension means to secure said head upon said shank, said tension means being adapted to permit of a slight angular movement of said head relative to the tension 85 means upon impact of the cutting head against the rock.

3. In a rock drill, a shank, a separable cutting head adapted to be secured to the lower end thereof, the contiguous faces of 90 said shank end and head being flat, one of said faces being provided with recesses, the other of said faces being provided with correspondingly shaped projections, and tension means to secure said head upon said 95 shank, the tension means being adapted to permit of a slight angular movement of the head relative to said tension means upon impact of the said head against the rock.

4. In a rock drill, a shank, a separable 100 cutting head, and flexible tension means to secure said head to said shank, said tension means being adapted to permit of a slight angular movement of the head relative to the shank upon impact of said head against 105 the rock.

5. In a rock drill, a shank, a separable cutting head, flexible tension means adapted to secure said head to one end of said shank, said tension means being adapted to permit of a slight angular movement of said head relative to the shank upon impact of said head against the rock, and means to apply tension to said tension means located at or 110 near the outer end of said shank.

6. In a rock drill, a shank, a cutting head adapted to fit snugly against a correspondingly formed end of the shank, means to prevent lateral and rotational displacement of said head, and flexible tension means to secure said head to said shank by the application of simple backward pressure thereon, said tension means being adapted to permit of a slight angular movement of the head relative to the shank, upon impact 120 of said head against the rock.

7. In a rock drill, a shank, a separable cutting head adapted to be secured to the lower end thereof, the contiguous faces of 130 said shank end and head being flat and one

of said faces being provided with recesses, the other of said faces being provided with correspondingly shaped projections and flexible tension means to secure said head upon 5 said shank, said tension means being adapted to permit of a slight angular movement of the head relative to the shank upon impact of said head against the rock.

8. In a rock drill; the combination of a 10 shank, a separable head adapted to be held thereto, and means for holding the head to the shank and regulating the intimacy of contact therebetween comprising a bolt passing through the shank and a wire extending 15 from the head to the bolt, said wire being secured to the head and bolt.

9. In a rock drill, the combination of a 20 longitudinally perforated shank, a separable head adapted to be held thereto; and means for holding the head to the shank and regulating the intimacy of contact 25 therebetween comprising a bolt passing transversely through the shank and a wire extending from the head, through the perforation in the shank, to the bolt, said wire being secured to the head and the bolt.

10. In a rock drill; the combination of a shank having a recess near its rear portion, a separable head adapted to be held to said 30 shank, and means for holding the head to the shank and regulating the intimacy of contact therebetween comprising a bolt passing transversely through the shank and spanning the recess therein, and a wire ex-

tending from the head to the bolt and being 35 secured to the head and bolt.

11. In a rock drill, the combination of a longitudinally perforated shank having a recess near its rear portion, a separable head adapted to be held to said shank and 40 means for holding the head to the shank and regulating the intimacy of contact theretwixen, comprising a bolt passing through the shank and spanning the recess therein and a wire passing from the head, 45 through the perforation in the shank, to the bolt, said wire being secured to the head and the bolt.

12. In a rock drill, the combination of a shank provided with recesses upon its end, 50 a separable head adapted to be held to said shank, means for preventing rotational displacement of said head comprising bosses projecting from said head and adapted to fit into the recesses in said shank, and means 55 for holding the head to the shank and regulating the intimacy of contact theretwixen comprising a bolt passing through the shank and a wire extending from said head to said bolt and being secured to the head and the 60 bolt.

In testimony whereof I affix my signature in presence of two witnesses.

ROBERT HUTCHISON ANDERSON.
